ATT'Y 6.

UNITED STATES PATENT OFFICE.

JAMES S. TURNER, OF CHELMSFORD, MASSACHUSETTS.

MACHINE FOR COVERING ROLLS WITH LEATHER.

SPECIFICATION forming part of Letters Patent No. 609,597, dated August 23, 1898.

Application filed March 9, 1898. Serial No. 673,224. (No model.)

To all whom it may concern:

Be it known that I, JAMES S. TURNER, of North Chelmsford, in the county of Middlesex and State of Massachusetts, have invented 5 certain new and useful Improvements in Machines for Covering Rolls with Leather, of which the following is a specification.

This invention relates to machines for applying leather coverings to rolls such as those, 10 used in spinning-machines.

The invention consists in the novel features of construction and arrangement which I shall now proceed to describe and claim.

Of the accompanying drawings, forming a 15 part of this application, Figure 1 represents a side elevation of a machine constructed in accordance with my invention. Fig. 2 represents a detail end view of the acting portion of one of the stretching-arms. Fig. 3 represents a section on line 3 3 of Fig. 2. Fig. 4 represents a view of the under face of the parts shown in Figs. 2 and 3.

The same reference characters indicate the same parts in all the figures.

25 The purpose of the machine is to stretch a leather band over the periphery of a wooden or metal roll, the band being naturally shorter than the length of said periphery; and to this end are employed a pair of oppositely-disposed 30 claws or arms having provisions for engaging the ends of the leather band and means for moving said arms to draw the ends of the band together.

Referring to the drawings, I have represented a base *a*, upon which are mounted two standards *b b*, joined at their upper ends by a brace *c* and journaling a shaft *d*, on which are mounted two worm-gears *e e*, having, respectively, right and left hand threads. Between ears *b' b'* on the two standards *b* are pivoted two levers *f f*, formed at their upper ends with worm-gear segments *f' f'*, which mesh with the worms *e e*. At the lower ends of said levers are pivoted the two stretching 45 arms or claws *g g*. In the middle of the base are mounted standards *h*, supported on a slide *h'*, which is arranged to move transversely of the base. Through the center of said standards extend posts *i*, having screw-threaded 50 stems engaged by adjusting-nuts *j*, which may be turned to raise and lower the posts. The posts *i* carry recessed blocks *i'* at their upper

ends, adapted to support the trunnions *k* of a roll *k*, which it is desired to cover with leather.

55

The operating ends of the arms *g* are provided with removable end-pieces *g'*, secured to the arms by screws *g²* and thickly studded with pins *g³ g³*, having pointed lower ends. When the arms are used to stretch the leather 60 band over the roll, the pins *g³* become embedded in and firmly engaged with said band.

The machine is operated by first placing the roll *k* in its supports, as shown in Fig. 1. The leather band *m*, which is to form the peripheral covering of the roll, is then placed around the roll, its inner surface or the surface of the roll having, preferably, been first coated with cement or glue, and the ends of the arms *g* are brought into contact with the 70 leather near its ends. Then by rotating the shaft *d* in such a direction as to cause the arms to move toward each other the pins *g³* become embedded in the leather and a continued rotation of the shaft causes the ends 75 of the band to be brought together. The leather may then, if desired, be secured to the roll by means in addition to the cement or glue while the stretching-arms are still engaged with its ends and said arms then retracted by a reverse movement of the shaft *d*. When a wooden roll is being covered, the ends of the band may be tacked to the wood. *c' c'* are two hooks suspended from the brace or cross bar *c* and designed to support the 80 ends of the arms *g g* when the latter are not in use.

I claim—

In a machine of the character described, a pair of oppositely-disposed stretching-arms, 90 and end pieces formed to fit said arms and removably secured to the ends thereof, the said end pieces being thickly studded on their acting-faces with pins which have pointed ends adapted to become embedded in the ends 95 of a leather band for the purpose of stretching the same over a roll.

In testimony whereof I have affixed my signature in presence of two witnesses.

JAMES S. TURNER.
